COMBINED BOOT JACK AND BOTTLE OPENER OR SIMILAR ARTICLE

John H. Brackin, Columbus, Ohio

Application September 3, 1948, Serial No. 148,464

Term of patent 14 years

(Cl. D7—2)

To all whom it may concern:

Be it known that I, John H. Brackin, a citizen of the United States, residing at Columbus, in the county of Franklin and State of Ohio, have invented a new, original, and ornamental Design for a Combined Boot Jack and Bottle Opener or Similar Article, of which the following is a specification, reference being had to the accompanying drawing, forming part thereof.

Figure 1 is a top plan view of a combined boot jack and bottle opener or similar article, showing my new design.

I claim:

The ornamental design for a combined boot jack and bottle opener, or similar article, as shown.

JOHN H. BRACKIN.
